[57] CLAIM

The ornamental design for a combined ball hitch and vehicle carrier for golf club carts having vertical mounting coupling, substantially as shown and described.

DESCRIPTION

FIG. 1 is a top plan view of a combined ball hitch and vehicle carrier for golf club carts having vertical mounting coupling showing my new design.

FIG. 2 is a rear elevational view thereof.

FIG. 3 is a front elevational view thereof.

FIG. 4 is a bottom plan view thereof.

FIG. 5 is a side elevational view as taken from the left side thereof.

FIG. 6 is a side elevational view as taken from the right side thereof.
